(57) **CLAIM**

I claim the ornamental design for a personal air cooling tower, as shown and described.

DESCRIPTION

FIG. 1 is a top-front perspective view of a personal air cooling tower;

FIG. 2 is a top-rear perspective view of the personal air cooling tower of FIG. 1;

FIG. 3 is a front view of the personal air cooling tower of FIG. 1;

FIG. 4 is a rear view of the personal air cooling tower of FIG. 1;

FIG. 5 is a left side view of the personal air cooling tower of FIG. 1;

FIG. 6 is a right side view of the personal air cooling tower of FIG. 1;

FIG. 7 is a top view of the personal air cooling tower of FIG. 1; and,

FIG. 8 is a bottom view of the personal air cooling tower of FIG. 1.

The broken lines in the drawings illustrate portions of the personal air cooling tower that form no part of the claimed design.
